C. HOSKINS

ROOF FLASHING

Filed June 15, 1925

Inventor

Cicero Hoskins
Arnold & Thompson
Attorneys

UNITED STATES PATENT OFFICE.

CICERO HOSKINS, OF QUINCY, ILLINOIS.

ROOF FLASHING.

Application filed June 15, 1925. Serial No. 37,308.

To all whom it may concern:

Be it known that I, CICERO HOSKINS, a citizen of the United States, residing at Quincy, in the county of Adams and State of Illinois, have invented certain new and useful Improvements in Roof Flashing; and I do hereby declare the following to be a full, clear, and exact description of the same, reference being had to the accompanying drawings, forming part of this specification.

This invention relates to improvements in raggles blocks or flashing receptacle or ragger.

An object of the invention is to produce a raggles block having a flashing receiving slot so devised as to permit the flashing to be quickly and securely locked therein.

More particularly the invention contemplates a raggles block having a flashing receiving slot provided with a flashing locking means, such means comprising a re-entrant recess merging in said slot.

The flashing is formed with a locking projection or tongue which will engage in said re-entrant recess when the flashing is inserted in the slot and when said tongue is engaged in said recess the flashing is securely locked in the raggles block.

In the accompanying drawings—

Figure 1 is a vertical sectional view of a wall and adjoining roof showing the preferred embodiment of the present invention; and

Fig. 2 is a perspective view showing a modified form of the invention.

For purposes of illustrating the invention, a section of a vertical wall 10 and a portion of an adjoining roof 11 are shown, the raggles blocks 12 being set in the wall 10 at the proper height. Usually these blocks are of sufficient size to occupy the space that would normally be occupied by two bricks. Their size, however, as well as the distance between adjacent blocks in the wall, can be varied as desired.

In most instances a cant strip 13 is placed in the angle formed by the adjoining surfaces of the wall 10 and roof 11 in order to support the flashing at the proper inclination to the roof and thus eliminate abrupt angles in the flashing. This cant strip may, however, be omitted, permitting the flashing to lie against the face of the lower portion of the wall 10, but this will require the flashing to be bent at right angles at the

point where it is turned to extend over the roof.

This flashing 14 extends from the roof up over cant strip 13 and into a slot 15 in the raggles block 12 and to securely maintain the flashing in this position, said slot has a pre-formed locking means such as a re-entrant portion 16 in which a projection or locking tongue 17 on the flashing engages. With the tongue 17 locked behind the lip 18 of the re-entrant recess, the flashing will be securely held in place while being mopped or pasted to a base flashing or if the flashing is to remain unpasted to compensate for contraction and expansion, there will be little or no danger of it being displaced from raggles block 12.

As shown in Fig. 2, the tongue 17 can be offset at the proper angle to insure its engagement behind lip 18 of the re-entrant recess 16 but in the preferred form of block the slot 15 extends into the block 12 at an angle to the flashing supporting surface of cant strip 13, and the lip 18 is located in or intersects the plane of said surface of the cant strip. With this preferred form, the flashing will be slightly flexed as it is inserted in slot 15 but after tongue 17 passes the lip 18 said tongue will spring back and snap into the re-entrant recess. The flashing will then be securely locked in the raggles block.

I claim:

1. A raggles block for roof flashing adapted to be laid in a wall with its exterior face flush with the surface of said wall, said block having a slot therein to receive the flashing and said slot having a re-entrant portion extending into the body of the block to receive a projection on said flashing.

2. A raggles block for roof flashing having a slot therein in which said flashing is to be received, and said slot having a re-entrant portion for reception of a locking projection carried by said flashing, the bottom wall of said slot and the body of said flashing lying in different planes.

3. A raggles block for roof flashing having a slot therein in which said flashing is to be received, and said slot having a re-entrant portion for reception of a locking projection carried by said flashing, the bottom wall of said slot and the body of said flashing lying in different planes, and the lip at the entrance of said re-entrant portion of

the slot intersecting the plane in which said flashing is located.

4. A raggie block for the roof flashing covering a cant strip used in building construction, said block having a flashing receiving slot therein, said slot extending in a plane at an angle to the exposed face of the cant strip, and said slot having a re-entrant recess in which a locking projection ¹¹ ₁₀ on said flashing is received.

5. A raggie block for the roof flashing

used to cover a cant strip in building construction, said block having a slot therein offset with respect to the plane in which the exposed face of the cant strip is located, and a re-entrant recess merging into said slot, the lip at the entrance of said re-entrant portion projecting into the plane of the exposed surface of the cant strip whereby the portion of the flashing extending into ¹² ₂₁ the slot will be flexed by said lip.

CICERO HOSKINS.
